UNITED STATES PATENT OFFICE.

HARRY E. TOLLIVER, OF MANGUM, OKLAHOMA.

FAN SCROLL FOR COTTON EXHAUSTERS.

Application filed August 25, 1925. Serial No. 52,435.

This invention relates to cotton exhausters wherein exhaust fans are used, and particularly to the scroll which forms the outer wall of the casing of the exhaust fan.

5 Exhausters having exhaust fans therein as described are used in cotton gins for the purpose of handling the cotton from the wagon to the gin stands, and as the cotton has more or less sand in it this sand 10 acts to cut these scrolls and the scrolls have to be changed in a very short time on an average of every three days because of the fact that the scroll has been cut out by the sand projected by the fan against the scroll. 15 It is hard to make this change inasmuch as the scrolls are all made in one piece of iron and are expensive. Sometimes these scrolls are cut away within twenty-four hours and in all circumstances these scrolls are a constant trouble, annoyance and expense. 20 When a hole is blasted through this scroll by the impact of the sand particles, the sand flies all over the gin machines in the gin house.

25 With these objections in view, the object of the present invention is to provide a sectional scroll which is so constructed that the sections may be easily put in place or removed so that there is no necessity of removing the entire scroll if any certain part 30 of it wears out but the section may be readily removed and readily replaced by a new section.

35 A further object is to provide a section of such form that the sand will not be discharged through the joints between the sections.

40 A still further object is to provide scroll sections of cast iron to thereby increase the life of the scroll.

Another object is to so form the scroll sections in cross section as to give the dirt and sand a chance to spread out and not cut all in one place.

45 Other objects will appear in the course of the following description.

My invention is illustrated in the accompanying drawing, wherein:—

50 Figure 1 is a vertical sectional view through the fan casing of a cotton exhaustor constructed in accordance with my invention;

Figure 2 is a transverse section on the line 2—2 of Figure 1;

55 Figure 3 is a perspective view of one of the sections of the scroll;

Referring to this drawing, it will be seen that I have illustrated therein an ordinary cotton exhaust of the usual type and having the usual scroll 10. This scroll is 60 spiral and is held in place by bolts. My invention consists in making this scroll of sections 11, these sections being of cast iron, cast to fit the curvature of the scroll, and the ends of each section are reduced to provide portions 12 adapted to lap over the reduced portions of the adjacent sections. These sections are formed with apertures 13 for the passage of bolts or other means whereby the sections may be held in place. 70 Transversely these sections are downwardly bulged so that the middle portion of the section 11 is thicker than the lateral portions, this inwardly bulged or somewhat convex face being designated 14. For ordinary 75 cotton exhausters the sections will be made eight and a half inches wide and one and a half inches thick at the middle and there beveled off laterally to a half inch on the edge. 80

These scrolls so formed in sections as above described have been in use for some time by me and not only do they not wear out as quickly as the ordinary scrolls but if by any chance a hole is cut through the 85 section by the sand the section may be readily replaced. Furthermore, the transversely bulged face of the scroll section acts to prevent the sand striking in one place but the sand tends to spread and thus wear 90 more evenly over the entire scroll section. By loosening four bolts 13, the section may be taken out and replaced in five minutes. 95

I claim:—

1. A fan casing for cotton exhausters including side walls, and a transversely extending scroll, the scroll being made in sections, each removably attached to the side walls and each removable independently of any other section. 100

2. A fan casing for cotton exhausters including oppositely disposed side walls, and a scroll, the scroll being made in independent sections, each section being reduced in thickness at certain edges to lap over the reduced edge of the next adjacent section, each section being removable bolted to the side walls independent of any other section and being independently removable. 105

3. A cotton exhaust having a fan casing, a scroll forming part thereof, the scroll being formed of a plurality of sections, each 110

- section being removably bolted to the fan casing independently of any other section and each section on its inner face being convex.
5. A cotton exhauster having a fan casing, a scroll forming part thereof, the scroll being formed of a plurality of sections, each section being removably bolted to the fan casing independently of any other section and each section having a convex inner face, the section being thicker at its middle than at its lateral edges.
5. As an article of manufacture, a scroll section for the fan casings of cotton exhausters, the section being of cast metal having reduced forward and rear edges whereby it may be lap jointed with adjacent sections having bolt holes whereby it may be attached and the inner face of the section being transversely convex.

In testimony whereof I hereunto affix my signature.

HARRY E. TOLLIVER.
